UNITED STATES PATENT OFFICE

136,626

DESIGN FOR A WATER PITCHER

Alexander F. Richards, Mayport, Pa.

Application September 3, 1943, Serial No. 111,060

Term of patent 14 years

To all whom it may concern:

Be it known that I, Alexander F. Richards, a citizen of the Dominion of Canada, residing at Mayport, in the county of Armstrong and State of Pennsylvania, have invented a new, original, and ornamental Design for Water Pitchers, of which the following is a specification, reference being had to the accompanying drawing, forming a part thereof.

Figure 1 is a side elevational view of a water pitcher, showing my new design;

Figure 2 is an end elevational view looking in the direction of the pouring spout;

Figure 3 is an end elevational view looking in the direction of the handle; and

Figure 4 is a top plan view of the water pitcher.

I claim:

The ornamental design for a water pitcher, as shown.

ALEXANDER F. RICHARDS.
